tion of Delaware

Original application June 19, 1937, Serial No.
149,054. Divided and this application Septem-
ber 25, 1941, Serial No. 412,266

11 Claims.

(Cl. 178—44)

The present invention relates to improvements in ultra high frequency circuits, and is a division of my application Serial No. 149,054, filed June 19, 1937, now United States Patent 2,260,529.

The invention provides, among other things, an improved ultra high frequency amplifier system which is easily balanced or neutralized against self-oscillation, and wherein only a large relative misadjustment of one circuit component with respect to the other circuit components will initiate oscillations.

An object of the present invention is to provide an improved type of coupling circuit comprising a pair of lines or sections thereof in energy coupling relation between a source of high frequency currents and a load. In the preferred embodiment of the invention, one of these pair of lines or sections of lines is constituted by a coaxial line arrangement.

A more detailed description of the invention follows in conjunction with the drawing, wherein:

Fig. 1 illustrates diagrammatically my improved type of ultra high frequency amplifier;

Fig. 1a illustrates a very general equivalent circuit given for the purpose of exposition; and

Fig. 2 illustrates diagrammatically and partly in section another embodiment of my improved ultra high frequency amplifier and employing my improved coupling circuit.

Like parts throughout the figures have been designated by like reference numerals.

Referring to Fig. 1 in more detail, there is shown an ultra high frequency balanced amplifier system comprising an electron discharge device 3 located within a grounded metallic substantially cylindrical container 2. The anode 1 of the amplifier device 3 is coupled to ground by means of plate 4 which is capacitively coupled to the container 2. The filament of device 3 is effectively connected to one end of a hollow metallic tube 5 which surrounds the lead 15 to the grid and the filament heating leads, not shown. The other part of the balanced system comprises a dummy circuit or artificial network, shown within the circular dotted line simulating the reactance condition of the electron discharge device and consisting of a pair of condensers arranged in the form of three metallic plates 8, 9 and 10. The center plate 9 simulates the grid and is connected to an input lead 16, one outer plate 10 simulates the anode and is grounded at container 2, and the other outer plate 8 simulates the filament of a live electron discharge device and is connected to one end of hollow tube 5, the

spacing between the plates 8, 9 and 10 determining the capacity between the elements of the dummy.

At a distance corresponding to resonance of the grid circuit, the grid lead 15 for the device 3 and the lead 16 for the dummy are short circuited by strap 6. An input circuit 7 is inductively coupled to the leads 15 and 16 within hollow tube 5 by means of a loop, as shown, the center of the loop being grounded to prevent eventual push-push effects in the amplifier system from being capacitively fed back into the input circuit. The push-push effects hereinabove mentioned refer to the excitation that could be exchanged between the wires 15, 16 and loop 7 due to capacitive coupling. By grounding loop 7 at its center, I thus prevent the loop from assuming a floating potential. It will thus be obvious that the input to the amplifier system is in push-pull relation, while the output is not in push-pull relation.

Another short circuiting strap 11 is provided across the grid leads 15 and 16 at a distance from the open end of cylindrical conducting tube 5 equal to half the length of the operating wave, in order to simulate a direct connection between the open end of tube 5 and the leads 15 and 16 insofar as these leads are considered to be in parallel or push-push relation. By "push-push" I refer to the condition wherein both leads 15 and 16 are "in phase" and act as one conductor of such a length that at the orifice of cylinder 5 a short-circuit effect is obtained. Since the hollow cylindrical conductor 5 is part of the tank circuit, the grid and the corresponding element of the network will "ride" on top of its oscillations. This is because the grid and the corresponding element of the network are made to have the same potential as the shell surrounding the two-wire line just as if they were directly connected to the shell, and thus "ride" on the shell potential. The reason the grids cannot be directly connected is because such a connection would prevent any sort of input feed.

The tank or tuned output circuit for the amplifier 3 consists of the anode capacity between plate 4 and the container 2 and a path of uniformly distributed inductance traced over the inner surface of container 2 and the outer surface of tube 5. The path of this tank circuit is traced by the arrows on the drawing. Tuning of the tank circuit is accomplished by means of movable metallic sliders 12, 13 which are simultaneously adjustable (uni-controlled) over the lengths of the container 2 and tube 5.

Output energy is derived from the amplifier system by means of connection 14 which is adjustable over the length of tube 5.

Before proceeding with a description of the operation of the push-pull amplifier system, it should be noted that the use of a dummy or artificial network is essential to the operation of the particular system illustrated in the drawing, otherwise it would not be possible to derive output energy from the tube 5. Since both the cathode of device 3 and the corresponding connection for the dummy from plate 8 are connected to the same location on the tube 5, it should be evident that the hollow sleeve-like tubular element 5 would be at neutral potential and the currents would flow in the same direction in these filament connections if a live electron discharge device were substituted for the dummy or artificial network. This will be more apparent from a consideration of Fig. 1a, which illustrates in a very general manner the equivalent circuit of Fig. 1, except for the omission of any reference to the arrangement for short-circuiting the push-pull oscillations. The elements of Fig. 1a corresponding to those in Fig. 1 have been given the same reference numerals except for a prime designation. The filament to grid and the grid to anode capacities of the electron discharge device have been designated in Fig. 1a as F—G and G—P, respectively.

In the operation of the balanced amplifier system, the filament of the electron discharge device swings at radio frequency potential instead of the anode. The grid of device 3 also swings in phase with the filament but at a higher amplitude, the grid connections being superimposed on the filament connections without prohibiting neutralizing or balancing. Putting it another way, any potential (such as from push-pull excitation), in addition to the shell potential, will under correct phase condition add up with the shell potential. The "in phase" condition of the grid with the filament is intrinsic with the response of the tube 3 to the excitation it receives. Since the plate or anode is grounded, the filament is in phase with the grid; the filament excites the shell and the grid "rides" on the shell. The input circuit 7 supplies push-pull signals to the two leads 15 and 16, lead 15 going to the grid of the grounded anode amplifier 3 and lead 16 going to the condenser group of the dummy simulating the characteristics of the device 3. The spacings between plate 9 and plates 8 and 10 are variable in nature to provide any desired degree of neutralization or balance. The excitation introduced on leads 15 and 16 by input circuit 7 causes device 3 to pass electron current which causes the filament of the electron discharge device to oscillate. The inductive coupling between input circuit 7 and leads 15 and 16 minimizes back reaction. Slider or strap 6 across the leads 15 and 16 tunes these circuit connections in push-pull relation. The strap 11 tunes the leads 15 and 16 in push-push so that the push-push drop is zero where the leads 15 and 16 emerge at the open end of tube 5, or with a controllable amount (either inductive or capacitive) as the need of the circuit requires. In this way, there is obtained a control of the regeneration which can offset the degenerative effect of the steady capacitive drop through the filament to grid and grid to anode capacities of device 3. In Fig. 2 all back reaction or capacity push-push feed back effect has been eliminated due to the use of double concentric lines.

In Fig. 2, the connections to the grid of device 3 and plate 9 of the dummy comprise portions of parallel hollow tubes 15" and 16" which are 100% coupled to the loop, shown in dotted lines, connected to input circuit 7. The currents in tubes 15" and 16" flow on the outside of these tubes from the grid of device 3 and plate 9 to the apertures 17 through which the input loop passes, and through the apertures to the inner surface of the tubes down to the input circuit. The arrows indicate the directions of the currents and the surfaces on which they flow. The input loop is here perfectly shielded and so coupled to the lines 15" and 16" that the original input lines 7 for push-pull operation form a perfectly continuous connection all the way to the grid and plate 9; the only requirement being that the loop from apertures 17 to bridge 25 be one-quarter wavelength long and the surge impedance of the inner conductors be equal to the surge impedance between its shells. The quarter wavelength distance indicated in Fig. 2 provides a high impedance for currents on the upper outside part of tubes 15" and 16" which tend to flow on the outside of these tubes past the apertures 17", and forces these currents to continue their flow on the inside of the tubes below the apertures. Small shield flaps 18 at the loop crossover at apertures 17, 17 are provided to prevent capacity between the input leads within tubes 15" and 16" and the output system.

I claim:

1. A coupling circuit for use between a source of high frequency currents and a load, comprising a section of two-conductor line each conductor of which is hollow, an electrically conducting bridge connected across said conductors, each conductor of said line having an aperture therein located from said bridge a distance equal to an odd multiple including unity of one-quarter wave-length at the operating frequency, and another section of two-conductor line passing through said apertures and in energy transfer relation to said first section of line, said load being connected to one of said line sections and said source being connected to the other of said line sections.

2. A coupling circuit for use between a source of high frequency currents and a load, comprising a section of two-conductor line each conductor of which is hollow, an electrically conducting bridge connected across said conductors, each conductor of said line having an aperture therein located from said bridge a distance equal to an odd multiple including unity of one-quarter wave-length at the operating frequency, said distances being equal, and another section of two-conductor line passing through said apertures and in energy transfer relation to said first section of line, said load being connected to one of said line sections and said source being connected to the other of said line sections.

3. A coupling circuit for use between a source of high frequency currents and a load, comprising a section of two-conductor line each conductor of which is hollow, an electrically conducting bridge connected across said conductors, each conductor of said line having an aperture therein located from said bridge a distance equal to an odd multiple including unity of one-quarter wavelength at the operating frequency, and another section of two-conductor line whose conductors extend into the interior of the hollow conductors of said first line and connect together through said apertures, said load being

connected to one of said line sections and said source being connected to the other of said line sections.

4. A coupling circuit for use between a source of high frequency currents and a load, comprising a section of two-conductor line each conductor of which is hollow, an electrically conducting bridge connected across said conductors, each conductor of said line having an aperture therein located from said bridge a distance equal to an odd multiple including unit of one-quarter wavelength at the operating frequency, and another section of two-conductor line whose conductors extend into the interior of the hollow conductors of said first line and connect together through said apertures, said source and said load being connected to said second and first sections of line respectively, on opposite sides of said apertures, whereby the currents in said second line flow over only that portion of the outside of the conductors of said first line between the load and said apertures.

5. A coupling circuit in accordance with claim 1 characterized in this, that said bridge is adjustable in position over the conductors of said first section of line.

6. A coupling circuit between a source of high frequency currents and a load comprising a pair of physically parallel tubular conductors having adjacently located apertures therein, leads extending within said tubular conductors and connected together through said apertures, a short-circuiting element bridging said pair of tubular conductors at a location approximately an odd multiple including unity of a quarter wavelength at the operating frequency from said apertures, said source and load being connected to said tubular conductors and leads on opposite sides of said apertures.

7. A coupling circuit between a source of high frequency currents and a load, comprising a pair of physically parallel tubular conductors having adjacently located apertures therein, leads insulatingly extending within said tubular conductors and connected together through said apertures, a short-circuiting element bridging said pair of tubular conductors at a location approximately an odd multiple including unity of a quarter wavelength at the operating frequency from said apertures, said source and load being connected to said tubular conductors and leads on opposite sides of said apertures.

8. A coupling circuit between a source of high frequency currents and a load, comprising a pair of physically parallel tubular conductors having adjacently located apertures therein, leads insulatingly extending within said tubular conductors and connected together through said apertures, a short-circuiting element bridging said pair of tubular conductors at a location approximately an odd multiple including unity of

a quarter wavelength at the operating frequency from said apertures, said source and load being connected to said tubular conductors and leads on opposite sides of said apertures, said load including a pair of structures of similar capacitive characteristics, one element of one structure of said pair being connected to a point on one of said tubular conductors, and a corresponding element of the other structure of said pair being connected to a point on the other tubular conductor, both of said points being substantially equally distant from said apertures.

9. A coupling circuit between a source of high frequency currents and a load, comprising a pair of physically parallel tubular conductors having adjacently located apertures therein, leads insulatingly extending within said tubular conductors and connected together through said apertures, a short-circuiting element bridging said pair of tubular conductors at a location approximately an odd multiple including unity of a quarter wavelength at the operating frequency from said apertures, said source being connected to said leads on one side of said apertures, and said load being connected to both of said tubular conductors on the other side of said apertures, the distances between said apertures and the points of connection on said tubular conductors to said load being equal.

10. A coupling circuit between a source of high frequency currents and a load, comprising a pair of physically parallel tubular conductors having adjacently located apertures therein, leads insulatingly extending within said tubular conductors and connected together through said apertures, a short-circuiting element bridging said pair of tubular conductors at a location approximately an odd multiple including unity of a quarter wavelength at the operating frequency from said apertures, said source being connected to said leads on one side of said apertures, and said load being connected to both of said tubular conductors at or near the ends thereof on the other side of said apertures, the distances between said apertures and the points of connection on said tubular conductors to said load being equal.

11. A coupling circuit between a source of high frequency currents and a load, comprising a pair of physically parallel tubular conductors having adjacently located apertures therein, leads insulatingly extending within said tubular conductors and connected together through said apertures, a short-circuiting element bridging said pair of tubular conductors at a location approximately an odd multiple including unity of a quarter wavelength at the operating frequency from said apertures, said source and load being connected to said leads and tubular conductors, respectively, on opposite sides of said apertures.
